Filed May 7, 1970, Ser. No. 22,877

Term of patent 14 years

Int. Cl. D14—02

U.S. Cl. D26—5

The figure is a front, top and right side perspective view of a magnetic tape cassette transport, showing my new design, the left side being a mirror image of the right side, and the back and bottom being conventionally plain.

I claim:

The ornamental design for a magnetic tape cassette transport, substantially as shown and described.
